US0D1048561S

(12) **United States Design Patent** (10) Patent No.: **US D1,048,561 S**
(45) Date of Patent: ** Oct. 22, 2024

(54) **TWEEZER**

(71) Applicant: **Huan Zhang**, Nanjing (CN)

(72) Inventor: **Huan Zhang**, Jiangsu (CN)

(**) Term: **15 Years**

(21) Appl. No.: **35/519,464**

(22) Filed: **Nov. 14, 2023**

(80) **Hague Agreement Data**

Int. Filing Date: **Nov. 14, 2023**

Int. Reg. No.: **DM/233791**

Int. Reg. Date: **Nov. 14, 2023**

Int. Reg. Pub. Date: **Dec. 22, 2023**

(51) **LOC (14) Cl. 28-03**

(52) **U.S. Cl.**

USPC **D28/55**

(58) **Field of Classification Search**

USPC D28/4, 7, 9, 55; D24/133, 143;
294/99.2

CPC B25B 9/02; A45D 26/00; A45D 26/0066;
G04D 1/021; A61B 2017/305
